FLUID FOUNTAIN DEVICE

John Warren Castino, River Forest, Ill.

Application September 23, 1939, Serial No. 296,266

3 Claims. (Cl. 132—74.5)

This invention relates to improvements in fluid fountain devices, and more particularly to a novel fluid fountain device of the type adapted to dispense and apply fluid used in the treatment of finger nail cuticle in the operation of manicuring.

An object of the invention is to provide a device of the type provided with a reservoir and fount of a material impervious to the action of the chemical fluid or composition to be held therein.

Another object of the invention is to provide a device of the type so constructed as to effectually seal the reservoir and fount against leakage.

Another object of the invention is to provide sealing means in a device of the type which will also act as a cleaner of the fount bore.

Other and further objects of the invention will appear as the description proceeds, reference being had to the accompanying drawing, in which—

Fig. 1 is a view in section of a fluid fountain device embodying the invention.

Fig. 2 is a view in perspective taken of the fount or plug and the sealing pin.

Fig. 3 is a view in section of a modified form of the invention.

In the drawing, the numeral 10 represents the device generally, having an outer shell 11, with an enlarged bore at the open end at 12 thereof, terminating inwardly in a shoulder 13. An inner container or reservoir 14, formed of glass or other vitreous material, has an annular outwardly deflected rim or ferrule 15, which latter is so proportioned as to rest snugly on the shoulder 13 within the enlarged bore 12 of outer shell 11. A compression washer 16 is held between the ferrule and a plug or fount 17, the latter in the preferred form of the invention being formed of cork or a similar material not affected by the cuticle fluid to be dispensed by the device. The fount 17 is of such a size relatively to the bore 12 of the shell 11, as to fit tightly therein, and has an annular flange 18, acting as a stop, both to seal the outer end of shell 11, and to provide a shoulder at 19 to seat the outer cap 20. A sealing pin 21 is inserted within the bore 22 of fount 17, and has an integral ring head 23, which rests against the inside of the closed end of cap 20, when the latter is in place. The fount 17 has an oblique face 26 on its outer or applicator end 27, 50

and it will be seen that the outer end 28 of the bore 22 is in a convenient place for the discharge of the cuticle fluid as the applicator end 27 is being used in pushing back the finger nail cuticle in the manicuring operation.

In use, the reservoir 14 is filled with the cuticle preparation or fluid, and it will be seen that with the pin 21 and cap 20 in place, the device may be conveniently carried in a handbag without the danger of leakage. When the cap and pin are removed, the oblique face 26 is applied against the top of the finger nails with a pushing movement of the end 27 against the cuticle. The fluid will pass by gravitational means to the nail surfaces and cuticle.

It will be understood that the device is capable of many modifications in structure and design, without departing from the spirit of the invention, within the scope of the appended claims.

Having thus described the invention, what I claim and desire to secure by Letters Patent of the United States, is:

1. A container, a shell for said container having an enlarged bore at the open end thereof forming an annular shoulder, a ferrule on the open end of said container normally seated on said shoulder, a compression washer, and a bored fount inserted in said shell bore for holding said ferrule between the washer and said shoulder.

2. A tubular container, a tubular shell for said container having an enlarged bore at the open end thereof forming an annular shoulder, a ferrule on the open end of said container normally seated on said shoulder, a compression washer, and a bored fount inserted in said shell bore for holding said ferrule between the washer and said shoulder.

3. A container, a shell for said container having an enlarged bore at the open end thereof forming an annular shoulder, a ferrule on the open end of said container seated on said shoulder, a compression washer, a bored fount inserted in said shell bore for holding said ferrule between the washer and said shoulder, an annular flange disposed medially of said fount, a cap for the fount adapted to seat against the flange, and a pin inserted in the fount bore as a cleaner and closure therefor and held in place by the cap.

JOHN WARREN CASTINO.
